Thomas P. Simpson

ATTORNEY.

UNITED STATES PATENT OFFICE.

GILBERT THORSEN, OF LETCHER, SOUTH DAKOTA.

SINGLETREE-CLEVIS.

SPECIFICATION forming part of Letters Patent No. 617,264, dated January 3, 1899.

Application filed March 15, 1898. Serial No. 673,896. (No model.)

To all whom it may concern:

Be it known that I, GILBERT THORSEN, a citizen of the United States, residing at Letcher, in the county of Sanborn and State of South Dakota, have invented certain new and useful Improvements in Singletree-Clevises; and I do declare the following to be a full, clear, and exact description of the invention, such as will enable others skilled in the art to which it appertains to make and use the same, reference being had to the accompanying drawings, and to the letters of reference marked thereon, which form a part of this specification.

The special object of the invention is to dispense with old styles of clevis in which rings, hoops, loose pins, keys, or nuts were employed and to enable the single or double tree to be placed on top of the evener, so as to work freely from side to side without being caught in anything; also, to connect all the parts permanently together, so that none can be lost, mislaid, or become loose. For this purpose I provide a double lock which is very easily manipulated, but cannot be unlocked by accident.

The invention will first be described in connection with the drawings, and then pointed out in the claim.

Figure 1 of the drawings is a side elevation showing the pin-arms thrown back. Fig. 2 shows the clevis closed, and Fig. 3 is a detail view of the stop.

In the drawings, A represents the body of the clevis, with the fixed projection B, end slots b b', and cross-pins b² b³, while C D represent hinged arms with pins c d at an angle there-

to and having shoulders c' d' near their free ends. The arms C D have rear slots c² d², which enable them to slide on the cross-pins 40 b² b³ in order to free the pin-shoulders c' d' from engagement with the body A.

E is a stop hinged on the pin b² and provided with a slot e, within which works the arm C. When this stop is raised, as shown 45 in Fig. 1 of the drawings, the arm C can be slid back on its cross-pin b², so as to allow the pin c to be disengaged and taken out of the slot. This permits the arm D to be slid back on its hinge-pin b³ and to be taken out 50 of its body-slot b'.

It will be thus readily perceived that I get a double lock on my clevis, which makes it very secure, while the clevis can be opened or closed with great facility.

These clevises will be made of different sizes and perhaps slightly changed to suit particular vehicles, but without departing from the principle of my invention.

What I claim as new, and desire to protect 60 by Letters Patent, is—

A singletree-clevis having the body A with projection B, the slots b b' and cross-pins b² b³, in combination with the two hinged arms C D and hinged stop E, the arms being provided with the shouldered pins F, G, at an angle thereto, all constructed and arranged substantially as shown and described.

In testimony whereof I affix my signature in presence of two witnesses.

GILBERT THORSEN.
